(57) **CLAIM**

The ornamental design for a bottle, as shown and described.

DESCRIPTION

FIG. 1 is a perspective view of a bottle embodying our new design;

FIG. 2 is a front view thereof;

FIG. 3 is a side view thereof;

FIG. 4 is a left view thereof;

FIG. 5 is a top view thereof;

FIG. 6 is a bottom view thereof; and,

FIG. 7 is a rear view thereof.

The broken lines shown in the drawings are for illustrative purposes only and form no part of the claimed design.
